Henry, Tinney of Pattersonburg, Va., assignee of J. W. Gibbs, of Albany, N. Y.

Letter Patent, No. 211, dated March 20th 1859.

I include several turnings with this Patent, making part of
the same.

I declare that I, Samuel W. Gibbs, of the City of Albany, and State of New York, have produced a new ornamental design for a Cooking Stove, which I call, The Old Dominion Air Tight Stove, and I hereby declare the annexed drawings to be a full and accurate delineation, of a stove constructed after my design, the side of the stove not shown in the drawing, being similar and symmetrical, with the side shown in the drawing.

What I claim as my invention, and desire to secure by Letter Patent, is the combination, and arrangement of ornamental figures and forms, represented in the drawings, making an ornamental design for a Cooking Stove.
